US00D772298S

(12) **United States Design Patent** (10) **Patent No.:** **US D772,298 S**
Carreon (45) **Date of Patent:** **** Nov. 22, 2016**

(54) **COMBINED WIRELESS SPEAKER AND VIDEO RECORDER**

(71) Applicant: **ZAGG Intellectual Property Holding Co., Inc.**, Salt Lake City, UT (US)

(72) Inventor: **Manuel Carreon**, Lehi, UT (US)

(73) Assignee: **ZAGG Intellectual Property Holding Co., Inc.**, Midvale, UT (US)

(**) Term: **15 Years**

(21) Appl. No.: **29/537,812**

(22) Filed: **Aug. 28, 2015**

(51) **LOC (10) Cl. 14-03**

(52) **U.S. Cl.**

USPC **D14/496; D14/203.3**

(58) **Field of Classification Search**

USPC D14/432, 434, 447, 357, 299, 496, D14/203.1–203.8, 149.155, 157, 188, 209.1, D14/217; D21/324, 328, 332, 333; 361/600, 361/679–686; 320/114, 115; 345/156–161, 345/905, 901; 439/529, 534, 929; 455/556, 455/556.2, 557

CPC G06F 1/16; G06F 5/00; H04N 5/225; H04N 5/40

(57) **CLAIM**

The ornamental design for the combined wireless speaker and video recorder, as shown and described.

DESCRIPTION

FIG. 1 is a front perspective view of the combined wireless speaker and video recorder in accordance with my invention;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is top plan view thereof; and,

FIG. 8 is a bottom plan view thereof.

The broken lines shown in FIGS. 1–8 are for illustrative purposes only and form no part of the claimed design.

1 Claim, 4 Drawing Sheets
